UNITED STATES PATENT OFFICE

159,906

WATCH

Otto Grun, New York, N. Y.

Application August 6, 1949, Serial No. 4,340

Term of patent 14 years

(Cl. D42—8)

To all whom it may concern:

Be it known that I, Otto Grun, a citizen of the United States, residing in the Borough of Manhattan, city, county, and State of New York, have invented a new, original, and ornamental Design for a Watch, of which the following is a specification, reference being had to the accompanying drawings, forming part thereof.

On the drawings,

Fig. 1 is a front elevational view of a watch embodying my design;

Fig. 2 is an edge elevational view of the watch shown in Fig. 1;

Fig. 3 is an elevational view of the watch shown in Fig. 1, looking at the rear face;

Fig. 4 is an edge elevational view of the watch, looking at it from the stem end; and

Fig. 5 is an edge elevational view, looking at the watch at the very bottom.

I claim:

The ornamental design for a watch, substantially as shown.

OTTO GRUN.
